MONROE GUETT, OF HARTFORD, CONNECTICUT, ASSIGNOR TO THE HART & HEGEMAN MANUFACTURING COMPANY, OF HARTFORD, CONNECTICUT, A CORPORATION OF CONNECTICUT.

PUSH-BUTTON CONNECTION FOR SNAP-SWITCHES.

1,230,480.

Specification of Letters Patent. Patented June 19, 1917.

Application filed October 22, 1916. Serial No. 128,154.

To all whom it may concern:

Be it known that I, MONROE GUETT, a citizen of the United States, residing at Hartford, in the county of Hartford and State of Connecticut, have invented certain new and useful Improvements in Push-Button Connection for Snap-Switches, of which the following is a specification.

This invention relates to push button connection for snap switches, the object of the invention being to provide simple means which is inexpensive in character and by which a push button or buttons can be connected with a switch operating lever in a rapid and easy manner.

In the drawings accompanying and forming part of the present specification I have shown in detail one convenient form of embodiment of the invention which will be set forth fully in the following description. I do not restrict myself to this exact disclosure; I may depart therefrom in several respects within the scope of the invention defined by the claims following said description.

Referring to said drawings:

Figure 1 is a sectional view of a switch equipped with a connection involving the invention.

Fig. 2 is an elevation of a portion of the switch operating lever and button connected together.

Fig. 3 is a vertical sectional view of the parts shown in Fig. 2, the section extending centrally through the bearing opening in the lever and showing the push button in initial and final positions, the arrow indicating the motion between the two.

Like characters refer to like parts throughout the three views, Fig. 1 being on a smaller scale than the other two figures.

There are various types of two-button snap switches in use which involve a lever and buttons connected with the lever for operating the same in alternation. In certain of these old switches the shank of the button is connected with the switch operating lever when in a certain position and then is turned through a certain are to interlock it with the lever. In this old form of switch the lever is generally of a peculiar construction, while the shank of the button is a little out of the ordinary. I provide a construction which can be made in a very

inexpensive manner and can be connected with facility and rapidity to the coating lever.

In Fig. 1 I have shown a switch operating lever 2 to which are connected the buttons 3 and 4 having shanks 5 and 6 connected with the outer ends of the said lever which is supported for oscillation between said ends in the box 7 of insulating material as common in the art.

As both buttons are the same in construction, a detailed description of one will apply to the other, and in this connection reference will be had to Figs. 2 and 3 which illustrates in part the button 3 and a portion of the lever 2. This button 3 has a shank 8 which I prefer to make from flat stock, as I can thus readily with the aid of suitable dies produce it from sheet material such for instance as brass. This flat shank may have the button 3 molded onto or otherwise associated with it. It sets when in operative position as shown by said Fig. 2 and in full lines in Fig. 3 edgewise or at right angles to the lever 2. The said shank 8 terminates in a laterally extending arm 9 furnished with a pendent extension 10, the shank 8, projection 9 and extension 10 being in the same plane from which, as will be inferred, the shank with said projection and extension can be easily made in the manner set forth. It should be noted that the projection 9 is at the extreme end of the shank which is the preferable construction and that it is also preferable that the pendent extension 10 should be located at the extreme end of the projection 9. The lever 2 has a bearing opening 11 to freely receive the projection 9, this projection constituting a flat pivot for connecting the lever and shank for relative swinging movement. The projection 9, although of less width than the diameter of the bearing or pivot opening 11 is not as wide as the shank and the extension 10 in turn is not as wide as the projection 9. This extension I might say acts as an effective stop to prevent accidental separation of the shank 8 from the lever 2 when the same are in working relation as shown in Fig. 2 and by full lines in Fig. 3.

As I have already observed the shank 8 with its button 3 can be quickly and easily connected with the lever 2. For instance the following procedure may be adopted to

bring about this result: The shank 8 will be horizontally disposed as shown by dotted lines in Fig. 3 and the extension or stop 10 will be inserted in the bearing opening 11. 5 When this is accomplished, the shank will be tipped up to the vertical position as illustrated by full lines in said view so as to bring the shank in proximity to the rear face of the lever, and at the same time introduce 10 the projection or pivot portion 9 into the bearing opening 11 and also bring the extension 10 in front of yet adjacent to the forward side of the lever 2, so that when the buttons extend through their customary perforations in the plate 12 on the front of the box 7 as indicated by Fig. 1, said buttons 15 cannot become accidentally separated from the switch operating lever 2.

What I claim is:

20 The combination of a switch operating lever having an approximately circular bear-

ing opening at one side of its center of motion, and a push button and its shank, the shank terminating in a projection fitted in said opening and the projection terminating 25 in a pendant extension constituting a stop to abut against one side of said lever, the shank, the projection and extension being flat and of sheet metal and all in the same plane, the shank being disposed edgewise to the other 30 side of the lever, said projection and extension being insertible through said bearing opening while the shank is at an angle to the operating lever and the parts being brought into assembled relation merely by a relative 35 lateral movement of the lever and the shank.

In testimony whereof I affix my signature in the presence of two witnesses.

MONROE GUETT.
